Donald G. Smellie, Canton, Ohio, assignor to The
Hoover Company, North Canton, Ohio, a cor-
poration of Ohio

Application September 25, 1933, Serial No. 49,331

Term of patent 14 years

To all whom it may concern:

Be it known that I, DONALD G. SMELLIE, a citizen
of the United States, residing at Canton, in
the county of Stark and State of Ohio, have in-
vented a new, original, and ornamental Design for
a Combination Motor Cap and Light Casing for
a Suction Cleaner or Similar Article, of which the
following is a specification, reference being had
to the accompanying drawing, forming part
thereof.

In the drawing:

Figure 1 is a side view of the combination mo-
tor cap and light casing for a suction cleaner or
similar article, showing my new design; and

Figure 2 is a front view of the invention; and

Figure 3 is a top view thereof.

I claim:

The ornamental design for a combination motor
cap and light casing for a suction cleaner or simi-
lar article, as shown.

DONALD G. SMELLIE.
